UNITED STATES PATENT OFFICE.

JULIUS FREDERIK GEORG POUL HARTMANN, OF COPENHAGEN, DENMARK.

ELECTRIC JET-WAVE COMMUTATOR AND INTERRUPTER.

Application filed May 19, 1925. Serial No. 31,351.

To all whom it may concern:

Be it known that I, JULIUS FREDERIK GEORG POUL HARTMANN, a subject of the King of Denmark, residing at Copenhagen, Denmark, have invented new and useful Improvements in or Relating to Electric Jet-Wave Commutators and Interrupters; and I do hereby declare the following to be a full, clear, and exact description of the same.

10 The present invention relates to apparatus in which a wave-shaped conductive liquid jet is used for effecting the closing or interruption of an electric circuit, and particularly to the so-called jet-wave commutators and interrupters which are described for instance in my United States Patents Nos. 1306335 and 1365491, and the main object of the invention is to provide an improved device for the cutting of the jet-bend of such apparatus in order to avoid or at least reduce the corrosive action of the commutation or interruption sparks on the jet cutting means.

15

In accordance with the invention the device for the cutting of the jet-bend consists of one or more sharp-edged members made of conductive material, preferably of high melting point, and of such shape and position that the interruption takes place between the jet and a part of the member distant from the edge which latter is thus screened from the corrosive action of the commutation or interruption sparks and will maintain its sharpness and be able to precisely cut the jet for long periods of time.

20 It has been found that the material of which this sharp member is made should preferably have a melting point above 2000° C. and that wolfram (tungsten) is well suited for this purpose.

Referring now to the accompanying drawings:

Figure 1 is a diagrammatic view of a jet-wave commutator,

25 Figure 2 is a front view of an embodiment of the invention,

Figures 3 and 4 are a front-view and a plan-view respectively of a second embodiment,

30 Figures 5 and 6 are a front-view and a plan-view respectively of a third embodiment,

Figure 7 is a diagram, and

35 Figure 8 is a front view of a jet-wave commutator including a fourth embodiment of the invention.

Figure 1 shows a commutator of known type which contains a wave-shaped liquid jet, or shortly a jet-wave J, preferably of mercury, which issues from a nozzle N and moves on in the direction of the axis of the wave-figure and strikes an electrode (main electrode), generally but not always, a two part electrode E₁, E₂, the component parts E₁ and E₂, of which ordinarily are separated by an insulating wall P having a sharpened edge which cuts the bends of the jet-wave. The jet-wave being during its movement towards the double electrode E₁, E₂ in constant touch with an auxiliary electrode E', will alternately connect this latter electrode with the electrode parts E₁ and E₂. The jet J, the double-electrode E₁, E₂ and the auxiliary-electrode E' thus form together a commutator which may be used for the rectification of an alternating-voltage. For this purpose the waves are generally produced by the co-action between a constant magnetic field F and an auxiliary alternating current which is synchronous with the voltage to be rectified. This current may be delivered from the secondary T of a transformer and sent into and out from the jet through the nozzle N and an auxiliary electrode E. Furthermore in order to make the commutator serviceable for the rectification of the alternating voltage the double-electrode is, and must be, adjusted at such a distance from the field, that the jet-bend is cut nearly at the moment in which the alternating voltage alters its sign.

The improvements more particularly described in the following mainly relate to the main electrode of such a jet-wave commutator, but may also be used in any other apparatus in which a jet-wave conductor is used for the closing or interruption of an electric circuit. It has been found that the wall P, Figure 1, can be entirely omitted, if the innermost edges of the two electrode-pieces E₁ and E₂, that is the edges a and b, are formed as protruding knife-edges for instance as shown in Figure 2. With this arrangement the commutation takes place in the following manner. The jet-wave, 105 travelling down towards the electrode, is first cut and very precisely cut, by one of the edges, in Figure 2 the edge a, but if the innermost surface of the electrode-part E₁ is nearly vertical the connection between the jet J and the electrode-part E is not broken before the jet-bend has advanced fur-

ther through the whole of the height of the electrode part E_1 and subsequently a further short distance. Just before the breaking of the connection, the latter is 5 maintained by a liquid string S , and the connection ceases through the breaking down of this string. Such a commutator has very valuable properties. Thus it has been found that a commutation of a very 10 high grade of exactness can be obtained. Furthermore the corrosive effect of the commutation spark is in a way made harmless as the spark is formed between the end of the jet bend c , Figure 2, and the lower edge 15 d of the electrode-part E_1 (or E_2). The spark thus does not attack the edge a (or b), from which it follows that the exactness of commutation is not diminished through the 20 wearing out of the electrode. If the innermost parts A and B of the electrode-sides E_1 and E_2 are made of a material of high melting point especially wolfram (tungsten) the wearing out of the electrode is, with 25 proper dimensions of the same, a very slow process.

A special form of an electrode made in accordance with the principle now explained is shown in Figures 3 and 4. The two electrode-sides E_1 and E_2 here consist each of a 30 series of knives or wedges of which, however, only the two innermost knives V_1 and V_2 are of consequence as regards the commutation-process, and only these two knives need be made of special material. The two 35 innermost knives or wedges may be insulated so that resistances or other electrical devices can be connected between them and the remainder of the electrode sides E_1 and E_2 respectively.

40 In the two embodiments of the invention described above the cutting of the jet bend does not take place in the middle-plan of the commutator. In certain cases this may be a disadvantage, which can be overcome by 45 constructing the electrode as shown in Figures 5 and 6, where between the two electrode sides E_1 and E_2 a knife or wedge V_0 of a conductive material is inserted. This knife is insulated from both electrode parts 50 E_1 and E_2 . The commutation now takes place in the following way. Just before the interruption of the connection between the jet J and that electrode side, in Figure 5 E_1 , which the jet is leaving, the connection is 55 upheld by the conductive middle-knife and the string S drawn out between that knife and the jet-bend. Shortly after the bend has reached the edge b of the other electrode side, the string breaks down and a commutation 60 spark appears. As above the spark does not attack the edge of the knife, which has cut the bend, but only the back of the knife, that is a part which is capable of 65 standing the influence of the spark much better than the edge and a part, the condi-

tion of which to a very high degree is unessential to the working of the commutator. The electrode sides E_1 and E_2 of the device shown in Figure 5, may be given any shape, but sides such as those shown in this figure 70 and consisting each of a series of knives or wedges have proved of advantage. It must be remarked that the edges a and b too are not attacked by the commutation spark. As a rule it is unnecessary to make the two 75 knives V_1 and V_2 or any of the knives of the two electrode-sides of a special material, while in commutators for higher loads the knife V_0 ought to be made of a material with a high melting-point, preferably tungsten. Often it will, however, be found advisable 80 also to use such a material for the two front knives V_1 and V_2 , because these knives are located near to the spark. As above one or more of the knives of the two electrode-sides may be insulated in order to make possible 85 the insertion of electrical contrivances between the knife and the remainder of the electrode or between the knives themselves. In a similar way electrical devices, say 90 resistances, may be inserted between the middle point of the electrode (the knife V_0) and the middle-point of the transformer-windings on which in case of a rectifier, the double electrode is working. In 95 Figure 7 there is shown such an arrangement with a resistance R connected between the knife V_0 and the middle-point of the transformer-winding T_1 , T_2 .

The insulated middle-knife may be divided 100 into several separate knives arranged in various ways. Figure 8 shows a jet-wave commutator having a triple-knife V_{01} , V_0 , V_{02} . The middle-knife V_0 is raised above 105 the side knives to such a level that the two strings S and S' break down simultaneously. Hereby two commutation sparks are formed instead of one, the wear due to the sparking thus being distributed on two knives and in 110 accordance herewith the load and voltage, which can be commutated by means of the electrode being increased. This complex knife-arrangement may be varied in many ways. For instance the middle-knife V_0 in 115 Figure 8 may be removed. The remaining knives V_{01} and V_{02} in this case could be left in the position shown in Figure 8 or they might be lowered to the level of the electrode-sides, their mutual distance being 120 simultaneously increased. If then they were connected with the electrode sides E_1 and E_2 , respectively either directly or through resistances the construction would be similar 125 to those shown in Figures 2 and 3.

Having thus fully described my invention I claim as new and desire to secure by Letters Patent:

1. In an electric jet-wave apparatus the combination of means for producing a conductive jet-wave, and a sharp-edged member 130

- of conductive material adapted to cut the bends of said jet-wave, said conductive member being so shaped and positioned that the interruption of an electric current passed through said jet-wave takes place between the jet-wave and a part of the said conductive member distant from its sharp edge which is thus screened from the corrosive action of the interruption-sparks.
- 10 2. The device of claim 1, in which the sharp-edged member is made of a conductive material having a melting point above 2000° C.
3. An electric jet-wave commutator, comprising means for producing a conductive jet-wave, an electrode which is in constant touch with the jet-wave, a double electrode, the two parts of which are adapted to be alternately connected with said first-named electrode through said jet-wave, and at least one sharp-edged member of conductive material adapted to cut the bends of said jet-wave when they approach said double-electrode, said member being so shaped and positioned that the interruption of an electric current passed through said jet-wave takes place between the jet-wave and a part of the said conductive member distant from the sharp edge of the same which is thus screened from the corrosive action of the sparks.
- 25 4. The device of claim 3, in which the sharp-edged conductive member cutting the bends of the jet-wave is insulated from and adjusted in the middle plane of the double-electrode coacting with the jet-wave.
5. The device of claim 3, in which three insulated knives of conductive material adapted to cut the bends of the jet-wave are arranged symmetrically in relation to the middle plane of the double-electrode with which the jet-wave co-acts and with such relative positions that the cutting of the jet-wave takes place simultaneously at two knives.
- 15 6. The device of claim 3, in which two knives of conductive material adapted to cut the jet-wave are arranged symmetrically in relation to the middle-plane of the double-electrode with which the jet-wave co-acts.
7. The device of claim 3, in which two knives of conductive material adapted to cut the jet-wave are arranged symmetrically in relation to the middle-plane of the double-electrode with which the jet-wave co-acts and each constitute part of one or other of the two sides of said double-electrode.
- 20 8. The device of claim 1, in which said sharp-edged member consists of tungsten.
9. The device of claim 3, in which said sharp-edged member consists of tungsten.

In testimony whereof I have affixed my signature.

JULIUS FREDERIK GEORG POUL HARTMANN.
